(57) **CLAIM**

The ornamental design for a display screen with graphical user interface, as shown and described.

DESCRIPTION

FIG. 1 is a front view of a first embodiment of a display screen with graphical user interface showing our new design; and,

FIG. 2 is a front view of a second embodiment thereof. The broken lines show portions of the graphical user interface and form no part of the claimed design.

1 Claim, 2 Drawing Sheets

FIG. 1

FIG. 2
